(57) **CLAIM**

The ornamental design for a disposal bin, as shown and described.

DESCRIPTION

FIG. 1 is a front left top perspective view of a disposal bin showing our new design;

FIG. 2 is a rear right top perspective view thereof;

FIG. 3 is a front elevation view thereof;

FIG. 4 is a rear elevation view thereof;

FIG. 5 is a right side elevation thereof, the left side elevation view being a mirror image thereof;

FIG. 6 is a top view thereof;

FIG. 7 is a bottom view thereof;

FIG. 8 is a front left top perspective view of a disposal bin insert shown in isolation for ease of illustration;

FIG. 9 is a rear right top perspective view thereof;

FIG. 10 is a front elevation view thereof, the rear elevation view being the same;

FIG. 11 is a right side elevation view thereof, the left side elevation view being the same;

FIG. 12 is a top view thereof;

FIG. 13 is a bottom view thereof;

FIG. 14 is a front perspective view of a disposal bin lid netting shown in isolation for ease of illustration;

FIG. 15 is a top view thereof, the bottom view being the same;

FIG. 16 is a front elevation view thereof, the rear elevation view, left side elevation view and right side elevation view all being the same; and,

FIG. 17 is an exploded view of the disposal bin.

The broken lines in the drawings illustrate portions of the disposal bin that form no part of the claimed design.
